P. F. O'CONNOR.

PLUNGER FOR SEWERS AND WATER CLOSETS.

No. 551,598.

Patented Dec. 17, 1895.

UNITED STATES PATENT OFFICE.

PATRICK F. O'CONNOR, OF WASHINGTON, DISTRICT OF COLUMBIA.

PLUNGER FOR SEWERS AND WATER-CLOSETS.

SPECIFICATION forming part of Letters Patent No. 551,598, dated December 17, 1895.

Application filed January 15, 1895. Serial No. 535,009. (No model.)

To all whom it may concern:

Be it known that I, PATRICK F. O'CONNOR, a citizen of the United States, residing at Washington city, in the District of Columbia, have 5 invented certain new and useful Improvements in Plungers for Sewers and Water-Closets; and I do hereby declare the following to be a full, clear, and exact description of the invention, such as will enable others 10 skilled in the art to which it appertains to make and use the same.

My invention relates to plungers for removing obstructions in sewer and water-closet pipes or connections, and its object is to provide a plunger which will effectually force the 15 obstruction downward or forward without inconvenience from top or back flow of the water and débris in sewer or other pipes during the plunging operations, and another object is to provide a plunger which can be readily extended in length to adapt it for 20 deep sewer-pipes, and while its capability of preventing up or back flow of water is secured its effectiveness is increased.

25 Another object is to prevent breaking of argillaceous sewer-pipes, and preventing unpleasant and injurious jars in operating the plunger.

Another object is to provide a plunger having either one or a plurality of moving plunger-heads, and which can, while being transported from the plumber's shop to the place of use and also back to the shop, have its parts screwed together so as not to dangle 35 about or move upon one another.

My invention will be fully understood from the following description and claims, in connection with the accompanying drawings, which form part of the specification.

40 Figure 1 is a front elevation of my improved plunger as adjusted for transportation from a plumber's shop to the place of use, and vice versa. Fig. 2 is an enlarged detail section of the upper portion of plunger as adjusted in Fig. 1, the extension portion of the plunger not being shown. Fig. 3 is a detail section of the pumping end of the plunger. Fig. 4 represents a vertical section of a water-closet hopper and its soil-discharging 45 pipe and my plunger with two plunger-heads and a sealing-plug or packed head in use for removing a stoppage in the soil-discharge

5 pipe or sewer-pipe with which it is connected; and Fig. 5 represents a vertical section of a sewer-trap pipe or other sewer-connecting water or soil pipe and my plunger shortened and provided with a sealing-plug or packed head and one plunger-head, and also with a single T-coupling, which is used when the plunger-rod is extended, as in Fig. 4. 60

As my plunger is capable of operating with either one or a plurality of moving plunger-heads it will be described first in the form represented in Figs. 2, 3, and 5, in which figures A designates a plunger-rod, which may 65 be solid or tubular. The tubular form is preferable on account of lightness and cheapness. This plunger-rod has a screw-thread a and a cross-piece or handle a' near its upper end. The screw-thread serves as a means 70 for fastening certain parts of the plunger firmly for transportation, as will be herein-after set out. On the lower end of this rod another screw-thread a² is provided, and upon this screw-threaded end a plunger-head B is 75 fitted, being confined between a removable socketed screw-threaded end stop-piece b and a thumb-adjusting nut b'. This plunger-head consists of two metal pieces c c' and a hollow rubber packing-ring c², said ring having 80 the form of a hollow sphere with upper and lower portions cut away. The piece c slips freely on the plunger-rod, while the piece c' is fitted by a screw-thread to said rod. By screwing the nut down against the upper metal piece 85 c the bulge of the packing-ring will be increased, and the opposite will be the result if the nut is turned back. Thus the plunger-head can be made to fit pipes of different diameters within a given range of diameter. 90

Where the differences of the diameters of sewer-pipes are considerable it is necessary to substitute a larger plunger-head for the smaller plunger-head, and therefore it is usual to provide a plurality of plunger-heads 95 for each plunger-rod, and to use one or the other as necessity requires. By turning back the nut b', and turning the piston-head backward, said head can be carried higher on the rod by the nut b'. 100

In all of the sizes of the plunger-head B it will be understood that the diameter of the moving head, including the rubber packing-ring c², must not be so great as to prevent suf-

ficient leakage, for easy and practical working, between it and the sewer-pipe in which it is being used during the backward movement of the plunger and its rod, or that the 5 rubber packing must be light and yielding enough to allow necessary leakage of either water or air, even if it extends to the inner surface of the sewer-pipe.

On the end stop-piece *b* a rubber sheathing *d* is fitted so as to prevent an iron contact 10 of the plunger-rod with the argillaceous sewer-pipe, and thus save the pipe from being broken or cracked, and also prevent unpleasant sounds and avoid injurious jarring of the 15 plunger and the operator. This plunger in order to operate practically should not be packed tight enough to prevent leakage of water between itself and the sewer-pipe. This is necessary in order that it may move 20 freely. Besides this, it is not always practical, even if it were desirable, to pack it thus tightly, because the sewer-pipe does not always have a truly circular passage-way, and therefore the plunger-head packing cannot 25 be made to pack the plunger-head so that water and débris will not escape and pass up by the plunger. This has been found to be the difficulty with forcing-plungers used by plumbers, and hence it has been necessary, 30 when the obstruction is considerably below the surface of the ground, to dig down to the stoppage in the sewer-pipe and take out the stopped pipe-section, in order to get at the obstruction. To obviate this great expense 35 and often injurious operation I have, while providing a plunger-head which will admit sufficient leakage between itself and the sewer-pipe to insure its practical operation, also devised an auxiliary plugging or packing 40 head *C*, in many respects similar in construction to the plunger-head proper *B*, but to be stationary while the plunger-head proper is moved downward and upward. This auxiliary plug or head comprises a tubular stem *f*, 45 adapted for the plunger-rod *A* to pass through and be steadied and guided thereby. This stem *f* has a long screw-thread *f'* and a short screw-thread *f''* on its outer surface, and on its upper end a double T-coupling, carrying 50 handle-pieces *f'* and having a short screw-thread *f''* on its inner surface, is applied. The screw-thread *f''* is to receive the screw-thread *a*, as will be hereinafter described. On the long screw-thread the packing plug 55 or head *C* is screwed, being adjustably confined on the stem by means of its sliding upper piece *c* and its screw-threaded piece *c'*, a long upper thumb-nut *g*, and a cap base-nut *g'*, the latter nut being packed at *g''*, so as to prevent 60 leakage of water along the piston-rod at the point where the piston-rod moves through the packing-plunger head. This packing-plunger head consists of two metallic portions *c'' c'''* and a rubber packing-ring *c'*, the same as 65 in the construction of the moving plunger-head proper. By screwing the nut *g* down, the rubber packing will be caused to bulge lat-

erally to the extent required to pack the auxiliary packing or plugging head *C* perfectly water-tight in the sewer-pipe or throat of a 70 water-closet hopper. It is the intention that this plugging-head shall not leak water, but shall act as a seal against the upward escape of water between itself and the surface against which the packing-ring of the head 75 binds and forms a water-tight joint. This combination of an adjustable sealing plug or head which remains stationary after being adjusted and its packing-ring fully set out or bulged, with a movable plunger-head which 80 may leak water between itself and the sewer-pipe and has its rod steadied and guided by the tubular stem of the auxiliary head or sealing-plug overcomes one of the greatest difficulties experienced by plumbers, while it 85 lessens labor and avoids loss of time, and saves property-holders a large amount of the expense charged for work done by them.

To operate with the plunger described and represented in Fig. 5 of the drawings, it is 90 only necessary to properly adjust the packing of the moving plunger by screwing down the nut, and then to adjust it and the head or plug into the sewer-pipe, and then screw down the thumb-nut *g* of the sealing-plug, so 95 as to secure a tight joint between it and the sewer-pipe. This done, the plunger proper must be moved by its handle *a'* rapidly up and down, until the obstruction is forced 100 down or along, and the free flow of waste water allowed. If found necessary, the handle of the tubular guiding-stem of the sealing-head may be adjusted to rest upon the top of the ground or upon the hopper of the closet.

To arrange the parts of the sealing-plunger described and shown in Fig. 5 for transportation from and to the shop and from and to the place of use, the tubular stem with its plunger-head attached is raised up to the screw-thread *a* and its coupling *f''* screwed upon the same, as illustrated in Figs. 1 and 2. By examining Fig. 1 it will be seen that an auxiliary moving plunger-head proper *D* is employed. To thus employ this head an extension-section *h* of tubular plunger-rod is provided, and on this section the plunger-head *D* is secured by means similar to those used for securing the lower plunger-head on its section of plunger-rod. The packing-ring of this plunger-head is adjusted by a thumb-nut 110 *m*, as shown. When the auxiliary plunger-head is provided as an adjunct of the construction of plunger shown in Fig. 5, two single T-couplings *n n'* and a double T-coupling *n''* are employed in connection with the 115 moving plunger-rod, and, after the stem of the sealing plug-head *C* is raised and screwed to the plunger-rod proper, the extension-section carrying the moving plunger-head *D* is unscrewed from the plunger-rod with the coupling *n''* attached to it, the T-head *n'* is moved up on the plunger-rod, the double T-coupling slipped on the handle of the tubular stem of the sealing plunger-head, and the sin-

gle **T**-coupling *n* screwed to or united with the single **T**-coupling *n'*, all as illustrated in Fig. 1. Thus adjusted the plunger can be transported conveniently and without its parts turning on one another.

It is important sometimes in removing stoppages in deep sewers to employ two moving plunger-heads on one line, as by this means increased action can be produced and there is greater certainty of removing the stoppage, and to thus employ two moving plungers it is only necessary to remove the lower cap-nut *b* of the plunger-head *B*, (shown in Fig. 5,) and to screw the double **T** couple upon the screw-threaded end of the plunger-rod, and then to screw the cap-nut *b* upon the screw-threaded end of the extension portion.

What I claim is—

1. A water closet or sewer plunger device, comprising a moving piston rod with piston head applied upon it, adapted to leak water between itself and the sewer pipe in which it is applied, and a packed water tight sealing plug or head arranged on it; the said latter head being stationary and serving for confining any back or up flow of water, while the moving piston head while allowing leakage between itself and the sewer pipe serves for forcing out any obstructions that may be in the pipe, substantially as and for the purpose described.

2. A water closet or sewer plunger device, comprising a moving piston rod with a plurality of piston heads applied upon it, and adapted to leak water between themselves and the sewer pipe in which they are applied, and a tubular stem fitted over the piston rod and having a packed water tight sealing plug or head attached to it; the said latter head serving for confining any back or up flow of water, the moving piston heads while allow-

ing leakage between themselves and a sewer pipe serving for forcing out any obstructions that may be in the pipe, substantially as and for the purpose described.

45

3. In the within described water closet and sewer plunger device, the combination of the piston, the piston rod provided with a screw thread *a*, the sealing plug provided with a tubular stem and a coupling connected to said stem and provided with internal screw threads adapted to be engaged by the said screw threads *a*, substantially as described.

4. In the within described water closet and sewer plunger device, the sealing plug having a tubular stem provided with a handle at its upper end, in combination with the main and auxiliary piston rod sections *A* and *h*, the coupling *n'* on the piston rod section *A*, and the coupling *n*, on the piston rod section *h*, and means for connecting said couplings, substantially as and for the purpose described.

5. In the within described water closet and sewer plunger device the combination of the screw threaded sectional piston rod, two plunger piston heads on said rod, a sealing plug or packing head and the removable screw threaded stop end *b*, substantially as described.

6. In the within described water closet and sewer plunger device the combination of the screw threaded sectional piston rod, a plunger head on said rod, a sealing plug or packing head, and the removable screw threaded stop end *b* sheathed with a yielding material *d*, substantially as described.

In testimony whereof I hereunto affix my signature in presence of two witnesses.

PATRICK F. O'CONNOR.
